UNITED STATES PATENT OFFICE.

WILLIAM J. WISWALL, OF PORTLAND, OREGON.

MANIFOLDING DEVICE.

1,349,865.

Specification of Letters Patent. Patented Aug. 17, 1920.

Application filed October 15, 1919. Serial No. 330,941.

To all whom it may concern:

Be it known that I, WILLIAM J. WISWALL, a citizen of the United States, residing at Portland, in the county of Multnomah and 5 State of Oregon, have invented a new and useful Improvement in Manifolding Devices, of which the following is a specification, reference being had to the accompanying drawings.

10 My invention relates to a class of devices wherein carbon sheets of common type are used in manifolding copies.

The object of my invention is to provide a device wherein continuous paper strips in 15 series may be supplied from a container and carbon strips between the original and the copy strips of the paper in like continuous manner. The objects, as well as other advantages, I accomplish by the construction, 20 combination and arrangement of parts illustrated in the accompanying drawings which form a part hereof.

Figure I is a side elevation of the device.

Fig. II is a longitudinal sectional elevation, on the line II—II of Fig. III.

Fig. III is a plan view.

Fig. IV is an elevation of a carbon roll in part with bearings in section.

Fig. V is a sectional view of a part on 30 the line V—V in Fig. III.

Like characters refer to like parts in the figures.

A case 7 of desired form and with a cover, is provided. Within the case a series of 35 supports 8 are secured. A series of trays 9 are deposited upon said supports. The trays receive paper strips 10 of continuous material which may be transversely perforated to facilitate its division into desired 40 parts. Forward of the trays are rollers 11 arranged in related positions to the trays 9 and paper 10 therein contained. A guide 12 is secured upon the inner side of one wall of the case and has bearings 13 in 45 which one of the respective ends of the rollers 11 is pivoted. The opposing wall of the case has rotatable thimble bearings 14 in alinement with the bearings 13. The bearings 14 have a tongue 15 and a coil 50 spring 16 therein. The rollers 11 have slots 17 in one end. The slotted end is inserted in the thimble bearing and pressed inwardly with the tongue in the slot and the opposing roller end is slid along the guide 12 until 55 it reaches its bearing 13 therein and the pressure on the spring 16 released, where-

upon the roller is in rotatable position in the bearing 13 and is rigid in the rotatable bearing 14. A gear train 18 is rigidly secured without the case wall upon the thimble 60 bearings 14 and has in connection therewith an idler 19 to arrange a rotation of the rollers in the same direction. Below the rollers 11 is a guide roller 20 arranged in relation to the lowest tray 9 and paper 10 65 therein. A gear 21 is pivotally mounted upon the outer case wall in position to engage the two uppermost gears of the train 18 and rotate them in the same direction. The gear 21 has an operating handle 22. 70 Upon the outer wall of the case a lever 23 is pivotally mounted. Upon one end it has a pivoted tension roller 24 arranged in a manner whereby the roller will engage the lowest gear of the train 18 and prevent the 75 rotation of the train members when the pinion is raised into such engagement by means of the lever and the gear 21 is not rotated. A spring 25 is formed and secured opposite the roller 24 in a manner to retain the roller 80 in engagement with the gear member and to retain it out of engagement as the roller is either raised or lowered in traveling engagement with the spring 25. Carbon strips 26 of common type are placed upon the rollers 85 11. The forward part of the case is provided with a writing table 27 and below it a container 28. A guide roller 29 is pivotally mounted at each end in the free ends of oscillating arms 30. Springs 31 are secured to the arms and case in position to cause the arms to depress the roller 29. In the forward part of the container 28 a transverse roller 32 is pivotally mounted in bearings 33 which are provided with 90 springs 34 to press the roller bearings upwardly in their sockets. A sprocket 35 is rigidly keyed on the end of the roller 32 and opposing this sprocket a second 95 sprocket 35' is pivotally mounted on a pin 100 secured to the outer wall of the case opposite the one with the gears 18. A continuous chain 36 extends about the sprockets 35—35'. Above the chain a longitudinal slotted guide 37 is rigidly secured along the 105 container and forward part of the case. Within the guide a grooved, slidale carrier 38 is placed. In the carrier 38 a vertically movable pin 39 is positioned with a spring 40 to press it upwardly, the pin being retained in the carrier by a collar 39' and also having its lower pointed end over the 110

upper path of travel of the chain 36. A tension spring 41 is secured at one end to the carrier 38 and its opposing end is secured to the case near its rear end. In the forward part of the container is a guide roller 42 pivotally mounted above the roller 32. A second guide roller 43 is pivotally mounted in bearings 44 slideable in sockets and provided with springs 45 to press the bearing rearwardly. Means 46 are provided to secure and retain the hinged bottom of the container 28 in position upon the container. A paper guide 47 is secured to the lower surface of the table 27.

It will now be seen that when tablets or blocks of folded continuous paper strips 10 are placed in the trays 9 and these on the supports 8 as shown in Fig. II, the rear upper ends of the strips in the upper trays are drawn forwardly over the opposing rollers 11 and the strip in the lowest tray below the roller 20 and thence outwardly beneath the guide roller 30, over the table 27. The bottom of the container having been removed, the strips of paper are drawn over the roller 42 and threaded between it and the roller 32. The bottom strip is then separated and all of the upper strips drawn downward and threaded between the rollers 32 and 43, while the bottom strip is allowed at the same time to project a desired distance into the container, the other strips projecting outwardly therefrom. While the paper strips are being drawn first over the table, the friction roller 24 is released from the gear train and the carbon strip rollers are rotated to pass carbon strips between the paper strips a desired distance, and the friction roller 24 again brought into engagement with the gear train to prevent the carbon strips from feeding farther outwardly. It is to be noted that the carbon strips in my device are passed between the sheets outwardly in a longitudinal direction, which differs from other devices, which usually place the carbon strips from a lateral direction. When the carbon strips are worn in one place the gear stop may be released and carbon strips passed outwardly a desired distance, as paper strips are drawn out, to supply a new carbon surface and the carbon strips locked as before. When the carbon strips pass out between the paper rollers of the container they may be torn away. When a section of the plurality of paper strips has been manifolded, the pin 39 is drawn outwardly to the end of the guide 37 and depressed into engagement with the chain 36. The pin is then moved rearwardly which causes the chain 36 to rotate the roller 33 rearwardly and it will then pass the upper strips outwardly as shown, and the bottom strip into the container. The lowest strip being a sufficient distance into the container it engages the bottom or prior fold of the

paper until it makes another fold, aided therein by the guiding spring 47. If it is desired to cut the carbon strips adjacent to the guide roller 29, then the pin 39 is applied at the rearward end of the guide 37 to the chain 36 and the chain drawn forwardly, which causes the roller 32 to rotate forwardly and the paper strips to be passed above it and released from the roller mechanism. The strips may then be raised and the carbon strips cut as desired. The paper strips are then threaded again in the rollers with new carbon strips between them as before described. I contend that the use of trays differs radically from the use of rollers to supply the paper strips, as the mechanism may draw the paper strips simultaneously and evenly, without friction or the necessity for greater power to do so. The object of the container is to supply a means for retaining one manifold copy as a secret record for auditing or other purposes, and the container may have locking means if desired.

I claim—

1. In a manifolding device of the character described, the combination therein of, a case, a container forwardly of the case, having a writing table on its upper surface, a series of trays in the case positioned one above the other and arranged to contain continuous strips of paper folded in zigzag pad form, and rollers in the outward part of the container arranged in a manner to allow the paper strips, one above the other, as drawn from the said trays outwardly over the table, to be threaded through the rollers and when these are rotated to allow the upper strips of the paper to be passed outwardly and the lowest strip to be passed into the container in folded form, for the purpose indicated.

2. In a manifolding device of the character described, the combination therein of, a case, a container forwardly of the case, having a writing table on its upper surface, a series of trays in the case positioned one above the other and arranged to contain continuous strips of paper folded in zigzag pad form, and rollers in the outward part of the container arranged in a manner to allow the paper strips, one above the other, as drawn from the said trays outwardly over the table, to be threaded through the rollers and when these are rotated to allow the upper strips of the paper to be passed outwardly and the lowest strip to be passed into the container in folded form, and a series of rollers positioned in the case forwardly of and in relation to the trays and table, said rollers being provided with strips of carbon paper and means to cause the same to be unrolled therefrom and passed between the paper strips longitudinally over the table a desired distance, for the purpose indicated.

3. In a manifolding device of the character described, the combination therein of, a case, a container forwardly of the case, having a writing table on its upper surface, 5 a series of trays in the case positioned one above the other and arranged to contain continuous strips of paper folded in zigzag pad form, and rollers in the outward part of the container arranged in a manner to allow 10 the paper strips, one above the other, as drawn from the said trays outwardly over the table, to be threaded through the rollers and when these are rotated to allow the upper strips of the paper to be passed outwardly and the lowest strip to be passed 15 into the container folded into pad form, a series of rollers positioned in the case forwardly of and in relation to the trays and table, said rollers being arranged to receive strips of carbon paper and to allow the same 20 to be unrolled therefrom and passed between the paper strips longitudinally over the table a desired distance, and mechanism appurtenant to the said rollers whereby the same may be rotated in either direction 25 simultaneously and locked in a desired position, for the purpose indicated.

WILLIAM J. WISWALL.
